SWIMMING RACE STARTING BLOCK

Thomas E. Beall, Jr., 5350 Edgewater Lane,
Bethesda, Md. 20814

Filed July 3, 1974, Ser. No. 505,611

Term of patent 14 years

Int. Cl. D25—99

U.S. Cl. D34—45

FIG. 1 is a perspective view of my new design that is symmetrical about a central vertical plane of a swimming race starting block;

FIG. 2 is a side elevation view thereof;

FIG. 3 is a top view thereof;

FIG. 4 is a bottom view thereof; and

FIG. 5 is a rear view thereof.

I claim:

The ornamental design for a swimming race starting block, as shown and described.
